UNITED STATES PATENT OFFICE.

DAVID GEORGE NORTON AND ALBERT DUROT, OF MANCHESTER, ENGLAND,
ASSIGNORS TO SIR JAMES FARMER & SONS LIMITED, OF SALFORD, MAN-
CHESTER, ENGLAND.

CLOTH-PILEING MACHINE.

1,418,199.

Specification of Letters Patent. Patented May 30, 1922.

Application filed December 9, 1920. Serial No. 429,564.

To all whom it may concern:

Be it known that we, DAVID GEORGE NORTON, a subject of the King of Great Britain and Ireland, and ALBERT DUROT, a citizen 5 of France, and residents of Adelphi Iron-works, Salford, Manchester, England, have invented certain new and useful Improvements in Cloth-Piling Machines, of which the following is a specification.

10 This invention relates to cloth plaiting or piling machines and has for its object to provide an improved construction of the means for traversing the winch back and forward during piling, the said means being 15 simple and reliable and capable of being lubricated and maintained in effective service condition.

Our invention comprises the combination with the usual cloth guide reciprocated 20 across the machine, of tubular rails extending the length of the machine upon which the winch carriage rides, right and left hand screws extending through the said tubular rails, means upon the carriage engaging the 25 said screws and means for rotating the winch as it is reciprocated by the screws.

Our invention further comprises the arrangement within each tubular rail of a 30 relatively short sleeve threaded on its exterior with a right and left hand screw, and feather keyed upon a power driven shaft within it, with means for holding the said sleeve in any desired position, where piling is to be effected, the sleeve being then 35 moved longitudinally to any desired new position so that successive batches of cloth can be piled in different places.

Referring to the two accompanying sheets of explanatory drawings:—

40 Figure 1 is a front elevation, partly in section, of a cloth piling machine constructed in one convenient form in accordance with our invention.

Figure 2 is a plan view of the machine.

45 Figure 3 is a sectional end elevation on the line AB of Figure 1 looking from left to right, showing a part of the machine only.

Figures 4 and 5 are respectively front elevation and plan illustrating the application 50 of our invention to the piling of cloth in several places by the one winch.

Figure 6 shows the winch carriage traversing means drawn to an enlarged scale.

Figure 7 illustrates the closure or union

of the ends of the right and left hand 55 threads of the screws employed to impart reciprocatory movements to the winch and guide eye.

The same reference letters in the different views indicate the same or similar parts. 60

The piling machine illustrated in Figures 1, 2 and 3 comprises a guide eye *a* carried by the member *b* which is clamped around but is free to slide along the tube *c*. The latter has a slot therein through which the 65 projecting part *d* of the member *b* can extend to engage the right and left hand screwed spindle *e* whereby the eye *a* is traversed back and forth across the machine. The right and left hand threads of 70 the spindle *e* are closed or united at each end by studs or directing pieces as *e'*, Figure 7, so that they form as it were a continuous thread extending and returning along *e* for imparting the said back and forth motion 75 to the eye *a*.

Extending along the sides of the machine are tubular rails *f*, *g* each having a slot 80 therein and co-axially through the said rails extend right and left hand screwed shafts *h*, *i*. The latter are rotated by the bevel wheels *j*, *k*, from the shaft *m* which is rotated by a chain *n* from the power shaft *p* having the belt pulleys *q* thereon. The shaft *m* also drives the shaft *e* by the spur 85 wheels *r*, *s*.

The winch *t* is carried by wheels *u*, *u'* which run upon the rails *f*, *g* before referred to, the wheels *u* being free upon the spindles *v* carrying the belt pulleys *w*. 90

A belt *w'* around said pulleys and the pulley *x* upon the winch spindle *y*, rotates the winch as the latter is reciprocated. Depending pieces *z* from the winch carriage *z* pass through the slots in the rails *g* and 95 engage the screws *h*, *i* whereby the winch carriage is reciprocated along the machine. The said screws have right and left hand threads with united ends as with the like threads of the spindle *e* aforesaid. 100

The interior of the rails *f*, *g* and tube *c* can be partly filled with lubricant for maintaining the screws in efficient condition and minimising friction without the danger of lubricant dropping on to the cloth. 105

The drum 3 serves to draw the fabric which is in rope form through the eye *a*. The fabric then passes over the winch *t*

which gives a wavy motion to the length of fabric suspended from the winch so as to pile the fabric in the well known manner.

The arrangement before described is particularly advantageous for allowing of the fabric being piled in different places to suit requirements. Thus in Figure 5, the fabric can be piled by the one winch in the receptacles 5, 6 and 7, and another winch can pile the fabric in the receptacles 8, 9 and 10.

To accomplish this the right and left hand screws *h* and *i* are formed on the exterior of sleeves as 11, Figure 6, and each sleeve is feather-keyed upon the power driven shaft 12. The ends of the sleeve abut against collars 13, each of which can be locked by a pin 14 which passes through a hole in the rails *f*, *g* in any predetermined position to ensure that the piling of the fabric takes place correctly in the different receptacles. In Figure 4, the winch is shown at the ends of its various lengths of traverse for piling the fabric into its different receptacles.

Having now described our invention

what we claim as new and desire to secure by Letters Patent is:—

1. In cloth piling machines, the combination with the usual cloth guide reciprocated across the machine, of tubular rails extending the length of the machine upon which the winch carriage rides, right and left hand screws extending through the said tubular rails, means upon the carriage engaging the said screws through slots in the 35 tubular rails, and means for rotating the winch as it is reciprocated by the screws, as set forth.

2. In cloth piling machines as claimed in Claim 1, the arrangement of the right and 40 left hand screws upon relatively short sleeves feather-keyed upon power driven shafts extending through the tubular rails, with means for locating the said sleeves in any desired position upon their shafts, as 45 set forth.

In testimony whereof we have signed our names to this specification.

DAVID GEORGE NORTON.
ALBERT DUROT.
